REVERSIBLE PRINTING PLATE

William H. Wolowitz, Washington, D. C.

Application December 31, 1946, Serial No. 719,427

4 Claims. (Cl. 101—369)

1
 This invention relates to printing plates, and more particularly to printing plates of that type which are adapted to be embossed and used in a printing device which is of the type normally inoperative but rendered operative when the printing plate is inserted.

Printing plates for use in such printing devices are usually of substantially rectangular shape and provided with a notch in one end to engage a pin to limit the inward movement of the plate in the printing device. The leading edge of the plate serves to operate a latch-trigger to release the printing device for operation, and the rear edge has attached thereto a cord, tape or other flexible means to serve as a pull when withdrawing the plate from the printing device.

Plates of this type have two disadvantages; first, they are non-reversible, and second, they are difficult to handle and to insert into the printing device.

The primary object of this invention is to provide a printing plate of this general character which is reversible so that letters, or other material to be marked, may be inserted from either side to receive the impression at any desired point.

Another object of the invention is to provide such a plate having means to facilitate its insertion and removal from the machine.

A further object of the invention is to provide a printing plate which is provided with means to ensure its proper positioning with respect to other plates when stored and not in use.

It is a further object to provide a plate of this nature which is preliminarily stiffened over a portion of its area so that when embossed with the desired indicia it will be stiffened over all of its area.

Other objects of the invention will be apparent from the following detailed description taken in conjunction with the drawings which accompany and form a part of this specification.

In the drawings:

Figure 1 is a side elevation of a printing device of the character with which the present invention is adapted to cooperate, parts being broken away to show the printing plate and its cooperative relation to the printing device;

Figure 2 is a partial bottom plan view of the structure shown in Figure 1, parts being broken away to show the plate, and

Figure 3 is a perspective view of the printing plate of the present invention.

Referring to the drawings in detail, the printing device illustrated herein is of a well known type used primarily to imprint, on given forms,

2
 the indicia contained on a plate commonly known as a "dog tag," which is a metal plate standardized as the means of identification of each member of the United States Army. Its use is broadened and enhanced by cooperation with the printing plate of the present invention by making possible the printing of letterheads, addresses on envelopes, and unlimited forms.

As the printing device is well known, it is not believed that a complete description of the printing device is necessary, as it will be sufficient for a full understanding of the present invention if only those parts with which the printing plate cooperates are described. The printing device 1 is provided with guides 2 to receive a printing plate 3, the plate being embossed with the required address or other legend, as indicated at 4. As shown, it comprises two pivoted members, one carrying the inked ribbon indicated at 5, and the other supporting a platen 6. Each of the sections has a handle portion, the two handles being juxtaposed to form a pistol grip 7. One of the sections is provided with an abutment 8 which is normally engaged by a latch 9 to prevent the sections from approaching one another when the handles are squeezed. Latch 9 is normally urged to latching position by means of a spring 10, and is attached to a trigger 11 by means of which the latch may be moved. The trigger is designed to be operated by plate 3 when the plate is inserted into the guides 2. A stop pin 12 limits the inward movement of plate 3.

The printing plate 3 has a body portion 13 of generally rectangular shape, having parallel side edges 14 and 15, and parallel ends 16 and 17. The end 17 of the body portion is notched at 18, the notch being to one side of the longitudinal center line through the plate and being designed to engage the stop pin 12 of the printing device. On the opposite side of the center a finger piece 19 extends from the end of the plate, one side of the finger piece being a continuation of the side edge 15 of the body portion of the plate. Between the finger piece and notch 18, the end wall forms a trigger-engaging surface 20 serving to strike and move the trigger to release latch 9 when the plate is inserted in the printing machine. The opposite end 16 of the body portion is provided with a notch 21, trigger-engaging surface 22, and finger piece 23, the respective elements being similar to those at the end 17 but reversely positioned, one side of the finger piece 23 being a continuation of the side edge 14 of the body portion.

Thus, it will be seen that the plate is reversible, the parts on the left side of the plate, as viewed

in Figure 2, assuming the identical position of those on the right when the plate is rotated in its own plane through an angle of 180°. This permits insertion of the plate with either end as the leading edge, and the address or legend embossed on the plate may be imprinted on an envelop or unlimited forms in any desired position, the printing distances from either side being limited only by the distance between the latch 9 and the notch 18 or 21 when the plate is positioned in the printing device as shown in Figure 1. This facilitates such operations as imprinting an address and a return address or printing of payrolls, rosters, or other forms, or printing on linens or similar surfaces.

It will be noted that finger piece 23 is shown longer than finger piece 19. This ensures the proper stacking of the plates when not in use, for if the plate is reversed in containers used for storage, it will be readily noticeable due to the fact that the body portion of the wrongly placed plate will extend beyond those properly positioned. With the embossing on all of the plates identically positioned, the longer finger piece also will serve as an indicator to ensure the correct orientation of the plate in the printing device.

The printing plate is made from relatively thin flexible material which is readily bendable. The embossed or other lettering serves to stiffen the body portion of the plate. However, some means must be employed to give rigidity to the finger pieces and it is also desirable to provide some desirable stiffening for the body portion. Therefore the finger pieces are corrugated as at 24, the corrugations running lengthwise of the finger pieces to strengthen them in the direction of greatest strain. A crosswise corrugation 25 is provided extending transversely of the body portion of the plate adjacent each end edge. Thus, the plate is stiffened along its extremities in its initial state and the embossing of the address completes the operation and provides a plate which is stiffened over its complete surface.

It will be noted from Figure 3 that the corrugations extend out of the plane of the plate on one side of the plate only. This is done so that an operator in picking up one of the finger plates may readily tell by the feel of the corrugations whether or not the plate is in the proper position for insertion into the printing machine. It is necessary that the corrugations extend out of the plane of the plate on the same side as the raised portion of the embossed address.

While in the above a preferred practical embodiment of the invention has been disclosed, it is obvious that many changes may be made from

the precise structure illustrated within the scope of the appended claims.

What is claimed is:

- 5 1. In a printing plate to be embossed for use in a printing device of that type normally releasably held inoperative by a latch but rendered operative by the insertion of the plate and having a pin to serve as a stop for said plate, a body portion, a stop-engaging notch in each 10 end of said body portion, a latch-engaging shoulder on each end of said body portion, and a finger piece extending from each end of said body portion, said stop-engaging notch, said latch-engaging shoulder and said finger piece on 15 one end of said body portion being reversely positioned with respect to those on the other end.
2. In a printing plate as claimed in claim 1, said plate being of flexible material, said finger pieces being corrugated longitudinally and said 20 body portion being corrugated along each edge adjacent said stop-engaging notches, said latch-engaging shoulders and said finger pieces.
3. In a printing plate, a body portion to be embossed with indicia for printing, and a finger 25 piece extending from at least one end thereof, said finger piece and said body near the edge thereof being corrugated, said corrugations being angularly disposed, whereby said plate when embossed for printing will be provided with stiffening means throughout its length and breadth,
- 30 4. In a printing plate as claimed in claim 3, said corrugations being out of the plane of the plate on one side of the plate only to indicate the printing side of said plate when embossed.

WILLIAM H. WOLOWITZ.
